SHUTTLE VALVE

Albert Girvin Winchester, Baltimore, Md., assignor to Gerotor May Corporation, a corporation of Maryland

Application August 2, 1944, Serial No. 547,790

4 Claims. (Cl. 137—144)

1

My invention relates to a hydraulic direction-rectifying valve, that is, a valve which will receive fluid flowing thereinto from different and reversible directions, but which will discharge the fluid, in uniflow manner, in a single, predetermined direction.

An object of my invention is to provide an efficient and reliable valve of the general type described, which is simple, compact, having only limited volumetric requirements, and sturdy, displaying long wear; which has only a limited number of moving parts and requires but minimum attendance and supervision, and hence has low maintenance and operational costs, and which at the same time involves entirely reasonable first cost.

Other objects and advantages will in part be obvious and in part pointed out hereinafter, in connection with the description of the construction disclosed in the accompanying drawings.

My invention accordingly consists in the several elements, features of construction and operational parts, and in the relation of each of the same to one or more of the others, all as described herein and as is fully set forth in the accompanying claims.

In the drawings:

Figure 1 is a view in side elevation of a preferred embodiment of my invention; Figures 2 and 3 respectively constituting top and bottom plans thereof and Figure 4 an end elevation, this on enlarged scale.

Figure 5 is a vertical longitudinal section on enlarged scale taken on line 5—5 in Figure 2; while

Figures 6, 7, and 8 are respectively, transverse vertical sections on enlarged scale taken on lines 6—6, 7—7 and 8—8 in Figure 1.

As conducive to a more thorough understanding of certain features of my invention, it may be noted at this point that need has arisen from time to time in many walks of industry for connecting hydraulic stand-by system-energizing equipment, which is normally blocked from a main hydraulic system, into that main hydraulic system. Now, this stand-by equipment frequently is reversible for supplying fluid in either direction to the main hydraulic system. The stand-by equipment usually is cut into the main system by valve means of the shift-over type when occasion requires. For simplicity, it is recognized as desirable to have the cut-in or shift-over valve last referred to operate either by or as an incident to energization of the stand-by equipment, so that the latter will be cut into the main system brought to operating speed. Now, difficulty is encountered in that the shift-over valve must always operate in a single direction in order to establish hydraulic circuits connecting the stand-by equipment to the main,

2

especially when the stand-by equipment itself is reversible in direction of energization. It is, therefore, necessary to employ means for impressing the positive pressure of the stand-by equipment, regardless of which end thereof is the momentary high pressure outlet, in but a single direction on the shift-over valve. The need for such equipment, and an adaptation of my present invention to the problem are suggested in a companion application for United States Letters Patent, Serial No. 547,788, filed of even date here-with, in the names of Albert Rivington Stone and Albert Girvin Winchester, now Patent 2,512,119 of June 20, 1950.

10 15 The manner of resolving these difficulties is therein shown, in schematic form, to comprise a direction-rectifying shuttle valve, certain novel details of which comprise the subject matter of the present application. It is of course readily understood that the co-pending application, just identified, discloses only a single one of many widely varied and diversified possible applications of my new valve construction.

20 25 An important object of my invention, therefore, is to remove or satisfy the disadvantages and difficulties referred to as encountered in the prior art, and to provide a hydraulic direction-rectifying shuttle valve which is simple and reliable in operation, and which serves effectively in connecting reversible-direction stand-by hydraulic equipment with a shift-over valve movable in but a single direction from its cut-out position.

30 35 Referring now more particularly to the drawings:

35 40 A valve casing portion 10 of metal is provided, which, for example, is generally rectangular in both longitudinal and transverse sections. End plates 11, 12, of the casing close off the respective ends of portion 10, and are secured thereto in any suitable manner, as by bolts 13. Elongated bolts 14 extend through casing portion 10 from the top, near the longitudinal walls thereof, and seat into a cooperating bottom casing member, not shown, such as a plate, header, or the like which covers the entire bottom area of the portion 10.

45 50 The valve casing comprising the several parts just mentioned serves to house two substantially separate and independent valves, except for certain features which are in common to the two valves, for convenience in construction, as will be more fully developed hereinafter, together with their attendant ports and sliding valve elements. The parts of one such valve are designated by the numeral prefix A, while the parts of the second valve are similarly designated by the prefix B.

55 60 To provide for such valves, the casing portion 10 has two adjacent longitudinal bores A15, B15 which, for example, have axes on a central ver-

tical plane through the casing. Parallel to these two bores and illustratively extending through the geometric center of casing portion 10 is a third bore 16. This bore is tapped as from the right end (Figure 5) of the casing but terminates short of the left end thereof. While bores A15 and B15 extend through end plates 11, 12, the bore 16 terminates at its right end against the solid wall of end plate 12. Bores A15, B15 are respectively defined, within casing 10, by sleeves A22, B22 let into the casing.

Sliding valve elements, in the form of piston valves A8, B8, and somewhat shorter than the length of the valve casing 10, are snugly received for limited longitudinal movement in corresponding bores A15, B15. The valve elements comprise reduced sections A9, A10, A11 and B9, B10, B11 defined between larger diameter end portions A12, A13, and B12, B13, and by similar intermediate portions A14, A16 and B14, B16, also of larger diameter.

Each valve element A8, B8 it will be understood is of the balanced, spool type. End plates 11, 12 permit ready installation of the spool-type piston valves, as well as providing ready access to the interior of the valve for repairs or overhauling, when occasion requires. Fluid inlets, more particularly described hereinafter, are provided at the several ends of these valve elements and are connected as to stand-by hydraulic equipment with which the valve is intended to cooperate. When the stand-by equipment is idle, the pressure exerted in each of the hydraulic lines by the stand-by equipment will be the same, and the valve elements are designed to stand in a neutral, centered position. When this condition is maintained, the relation of the valve ports, later to be described, and the sections of the valve elements is such that these ports are closed, and no flow occurs through the valve.

The valve elements are centered during their rest or inactive condition—their state of hydrostatic balance—by spring-urged followers, disposed one at each end of each valve element. Since the construction, dimensions and characteristics of the follower assembly is the same in each instance, the description of a single construction will suffice. I shall choose, for convenience, the assembly at the right (Figure 5) of the A piston. End section A13 is recessed at A17. Follower A18, disc-like in contour and of diameter sufficient to seat against the end face of section A13, is slidably fitted on bolt A19, which terminates at inner end in an enlarged cylindrical head A20. End plate 12 is internally threaded at A41 along bore A15 to receive the corresponding threads of shank A42 of enlarged nut A43, to which nut the bolt A19 is made fast as by threaded fit A31. A coiled spring A44 disposed about bolt A19 extends between follower A18 and bearing surface A45 fast to and forming part of nut A43, and serves, in conjunction with the spring of like characteristics at the other end of bore A15, to keep the valve element A8 normally in mechanical balance. The same construction is provided, and the same conditions maintain, at the other end of valve element A15 and at both ends of valve element B15.

For convenience, I will now discuss the construction, and with it the operation, of the B valve, shown at the bottom in Figures 4 through 8, inclusive. With it will be described certain features of construction which are in common to both the A and B valves.

In the aforementioned co-pending application,

the B valve is adapted to control connection of a hand-driven stand-by hydraulic pump to a main hydraulic system through shift-over valve means. While the hand pump is designed to be energized in either direction of rotation, the shift-over valve must be moved in but a single direction, all as has been suggested hereinbefore. Valve B serves admirably to fulfill these requirements.

10 To this end, the valve is provided with end ports B4 and B7 which serve to control the valve piston B8. Port B4 is disposed at the right end of casing portion 10 (Figure 5) at the end of bore B15, while port B7 is disposed at the left end thereof, also at the end of bore B15. Bore B1 leads directly and tangentially from the bottom of casing portion 10 to a corresponding port indicated by the same reference numeral B1. The relation of port B1 and bore B1 is best shown in Figure 8. This port B1 has generally the shape of an annulus in the longitudinal sleeve B22 (see also Figure 5) let into casing. The continuity of the sleeve is maintained, leaving port B1 substantially continuous and uninterrupted, by linking web portions B23, B24, B25 (Figure 8) which extend across the width of the annulus. Since the mechanical construction of all the ports arranged along the extent of the bores B15 and A15 are substantially the same, the details of the construction of the other ports, for simplicity, will in large measure be omitted, except for certain details which are unique to the particular port.

Referring now to Figure 5, it will be seen that 35 bore B1 near its lower end, is connected by a longitudinal passage B26, disposed near the bottom of casing portion 10, and extending to the right therein, to a bore B4 leading vertically near the right end of the casing to port B4 and the 40 end of piston B8.

It will be observed that in the present embodiment, I provide port B1 on the left (Figure 5) of the transverse center line of casing 10. Symmetrically therewith, I provide a bore B3 leading 45 to port B3, on the opposite or right side of the transverse center line. This construction is shown in Figures 3, 5 and 6. Bore B3 lets tangentially into port B3. In turn, port B3 lets into main bore B15.

Ports B1 and B3 constitute the pressure ports for connecting the valve with a suitable pressure source. In the case of my co-pending application already referred to, this is the hand-driven stand-by pump. At any particular moment during operation, one said port will be at high pressure and the other at low pressure, depending upon the direction of rotation of the pump. The pressures of the ports will be reversed upon reversal of direction of rotation of the pump.

60 In manner similar to that described with reference to bores B1 and B4, bore B3 is connected, for reasons which will be developed hereinafter, to port B7, disposed at the left end of bore B15, as seen in Figure 5. To this end, passage B29 (Figures 6 and 8) extends from bore B3 to the left, near the bottom of the casing to port B7. Passage B29 is not fully disclosed in the drawings, because of the direction in which the sectional views are taken; however, it is substantially the same as the construction heretofore described with respect to ports B1 and B4.

Centrally of bore B15 is port B2 (Figure 5), to which extends bore B2 from the bottom exterior (Figures 3, 5 and 7). This serves as an outlet 75 passage.

Ports B5 and B6 flank ports B3 and B1, respectively, on the right and left hand sides (Figure 5) and let into bore B15. Both ports B5 and B6 are in communication with central bore 16 (Figure 5). This bore is in turn let into transverse central bore 27 (Figures 5 and 7) which illustratively leads to a suitable disposal reservoir for excess and exhaust liquid. This reservoir takes the form of an expansion tank in the co-pending application.

In Figure 5 the solid line construction depicts rest position of the valve. The pressure on opposite ends of valve element B is the same. The valve element is in hydrostatic balance, and the pressure source, feeding in through ports B1 and B3, is at rest. In this condition of the valve, pressure ports B1, B3 are blocked by enlarged portions B14, B16 of the valve element. Both outlet port B2 and exhaust ports B5, B6 are sealed against the pressure ports and against the end ports by the interposition of these enlarged portions B14, B16 of the valve element. Rest conditions maintain.

Let us now assume, however, that pressure is applied across ports B1, B3 from any suitable external source, as for example, from the hand-driven pump of the co-pending application. Let us further assume that it is the port B1 which is at high pressure, port B3 being at low pressure.

With this understanding, fluid under positive pressure will enter bore B1. At passage B26, part of the fluid under pressure will course to the right in Figure 5, to the port B4. There it is let into bore B15 at the right end of sliding valve element B8. Impinging against end plate B18, and the end piston B8, it forces the piston to the left in Figure 5, with the aid of the coil spring at the right end, and against the compression force of the coil spring at the left end. Longitudinal movement is continued until a position of equilibrium is reached. Enlarged portion B14 moves to block port B6. Reduced section portion B10 is now moved to a position whereby high pressure port B1 opens directly into what properly may be termed the uniflow outlet port B2.

Fluid at the left end of piston B8 meanwhile is discharged as through port B7 and (see Fig. 6) through bores B29 and B3 which connect the discharge with the pump intake. Without suitable venting of the piston discharge, either the original condition of hydrostatic balance would remain substantially undisturbed, or if sufficient pressure were impressed on the right end of the valve to bring about a condition of incipient movement, damage or even rupture of the valve might quite likely occur.

Also, when valve piston B8 moves to the left, as seen in Figure 5, reduced section portion B11 uncovers ports B3 and B5, throwing B3 into connection with B5. A connection of the low pressure side of the pressure source, such as the pump, thus is established through bore B3, across ports B3 and B5 in bore B15, and through bores 16, 17 and 28 (see Figure 7), respectively, with a storage tank, bleeder fluid reservoir, or the like. In the co-pending application this connection ensures an adequate supply of fluid on the pump intake and avoids the pumping of air.

Let us now assume that the direction of energization of the pressure source, for example, the hand-driven pump in the co-pending application, is reversed in direction of rotation. B3 is now the high pressure side, while B1 is the low pressure side.

From bore B3 through passage B29 (Figure 6)

the pressure fluid courses to the left in Figure 5 to port B7. Entering bore B15 at port B7, this fluid forces the sliding piston valve B8 to the right, with the aid of the left-hand coil spring, and against the compression stresses in spring B24. Piston valve B8 is moved to the right, Figure 5, from its neutral or rest position. Ports B3 and B2 are thrown into communication with each other, by reduced section valve portion B10, and pressure fluid from high pressure port B3 courses directly to uniflow outlet port B2, and thence through outlet bore B2 to a suitable load, such as the shift-over valve described in the co-pending application. It is to be noted that a rectifying action takes place, in that uniflow discharge occurs through outlet port B2, regardless of the direction in which pressure is applied on pressure ports B1, B3. The direction of flow through B2 is the same, no matter whether it is B1 or B3 which is at high pressure. At the same time, fluid at the right end of bore B15 is expelled through B4, passage B26, and thence to bore B1. Ports B1 and B6 are open to each other, and thus the low pressure bore B1 is connected through the ports with conduit 16. As already mentioned (see Fig. 7) conduit 16 illustratively is connected with a fluid reservoir by the respective bores 27 and 28.

Fluid as from the low pressure side of the unidirectional load energized from B2 returns through passage 30 (Figures 3 and 7), communicating with the forward (left end in Figure 7) end of passage 27. The return fluid from the load thus courses to the junction of passages 27 and 28, and the greater part thereof returns through the bottom end of passage 28 to the low-pressure side of the power source, such as the hand-driven pump, not shown, although any excess will pass upwardly, to the expansion tank, also not shown.

Up to this point, the detailed discussion has dwelt entirely with the B section of the dual valve. We will now consider, in its turn, the A part of the valve giving particular attention to certain preferred structural details. Here use is made, for the discharge of the direction-rectified pressure fluid, of the same outlet port B2 as was used for the B valve. Similarly, use is made in common with the B valve, of the bore 16, passage 27, passage 28 and passage 30.

For convenience in design, one pressure lead through the plate or header (not shown) is provided at 31 (see Figure 3 near the left side). By means of a conduit formed by groove 32 illustratively in the bottom surface 33 of casing portion 10 and in the cooperating top surface of the header, not shown, the fluid is conducted from 31 to the right and upwardly in Figure 3, to the passage 34 (Figures 3 and 8). Passage 34 (Figure 8) communicates at its upper end with a lateral bore 35 leading tangentially to port A3 which is disposed in bore A15, on the left of the transverse center line in Figure 5. Passage 36 (Figures 6, 7 and 8) extends from A3 to port A7 disposed at the right end of bore A15 in Figure 5 and communicating with the corresponding end of piston A8. This passage is disposed substantially parallel with and in front of the plane of the paper in Figure 5.

Similarly, pressure lead 37 extends from the other lead of pressure source from the header (not shown) through groove 38 in casing bottom 33 to vertical passage 39 (Figures 3 and 6). Passage 39 connects at its upper end with lateral bore 40, which lets tangentially into port A1.

Port A1 opens into bore A15 on the right side of the transverse center line in Figure 5. Passage 41 extends from passage 40 adjacent port A1, to port A4 at the left end (Figure 5) of bore A15.

A port A2 is provided, disposed between pressure ports A1, A3 in Figure 5, and along the transverse center line therein. This uniflow outlet port A2 by-passes and is sealed from outlet passages 16 and 21. It connects with and empties through port B2, near the bottom of the latter.

Exhaust ports A5 and A6 are provided, symmetrically flanking, in Figure 5, the respective pressure ports A3 and A1. They are normally sealed from these latter ports when the piston valve is in its hydrostatically balanced or rest position. At all times these ports A5 and A6, in common with similar exhaust ports B5, B6 of the B valve, are in communication with bores or passages 16, 27, 28 and 30 which they share in common with the B valve components.

Normally, and just as is the case with the B valve, when the piston A is centered in hydrostatic balance, the pressure ports A1, A3 are sealed from uniflow outlet port A2. No fluid courses the system, and the system controlled by the valve is at rest. It is desired to ensure that regardless of the direction in which energization of the pressure system occurs, flow through the outlet port A2 will always be in the same direction.

To illustrate how this objective is achieved, assume that the source of pressure, such as the motor-driven pump in the copending application, is energized in such direction that port A3 is the high pressure port. In that case pressure fluid will enter at 31 in Figure 3, will course groove 32 to vertical passage 34 (Figure 8) to traverse passage 35, and thence tangentially into port A3. Simultaneously, part of this fluid will course from horizontal passage 35 through longitudinal passage 36 to the right in Figure 5 to the end port A7 at the right end of bore A15. With the aid of coil spring A44 and against the compression stress of the coil spring at the left end of the bore A15, this pressure fluid moves the piston A8 to the left in Figure 5. Port A3 is placed in communication, through reduced section portion A10 of piston A8, with outlet port A2, and discharges directly thereinto. This fluid courses down bore A2, sealed from and by-passing conduits 16 and 27, and communicating with outlet bore B2. Thence it passes to a suitable load. This, for example, may be the shift-over valve of the copending application, which must always be moved in but a single direction, regardless of the direction in which it is energized.

Fluid meanwhile is forced from the left end of bore A15, through port A4 and thence through passages 41 and 40 to port A1. By reduced section portion A11, port A1 is brought into communication with port A6. Any excess fluid is discharged from A1, through A6 into passage 16 while the rest returns to the pump through conduits 40, 39, 38 and 37.

Should now, the direction of rotation of the energizing source, such as the motor-driven pump, be reversed from that just described, the direction of operation is just reversed. A1 will now be the high pressure port; A3 the low pressure port.

Fluid will enter from the bottom header, not shown, under pressure at 37 in Figure 3.

Through groove 38 it passes to vertical passage 39 (Figure 6), and thence, at the upper end of passage 39, through lateral bore 40. The fluid enters tangentially into port A1. At first this valve is in hydrostatic balance, and port A1 is blocked by enlarged section portion A16 of piston valve A8. Part of the fluid entering through passage 40, however, travels through passage 41 to port A4, at the left end (Figure 5) of bore A15. This forces the piston valve A8, in manner now well understood, to the right in Figure 5. Valve portion A16 is moved so as to uncover port A1. Reduced section portion A10 of valve piston A8 permits direct communication between high pressure port A1 and uniflow outlet port A2. Through bore A2 and port B2, this port A2 connects directly with the unidirectional load. It will be seen that the effect of the valve A is to rectify the direction of flow of the pressure fluid, and to discharge the same in but a single direction of flow, regardless of the direction in which the source of pressure is energized.

Fluid forced from the right end of bore A15, as a result of movement of piston A8 to the right in Figure 5, escapes through port A7, through passage 36 to transverse passage 35 and thence to port A3. Reduced section portion A9 of piston A8 interconnects low pressure port A3 with exhaust port A5. This latter port in turn exhausts through bore 16 (left end in Figure 5) through transverse passage 27 (Figure 7) to vertical passage 28, which, as previously noted is connected with a storage tank or reservoir.

Through passage 30 (Figures 5 and 7) extending vertically from bottom face 33 of casing portion 10, return fluid from the pressure load, such as the shift-over valve, passes up to transverse bore 27 at the left in Figure 7, across this bore 27 to the right, and thence to vertical passage 28. Where bore 16 lets into bore 27, this exhaust fluid from the load mingles with the exhaust fluid from A5 or A6. At the junction of bores 27 and 28 (Figure 7), the exhaust fluid branches. The greater part courses down leg 28 and thence to the return side of the pressure energy source, such as the motor-driven pump. The excess fluid courses up leg 28, and thence to a suitable storage reservoir, such as an expansion tank. Later, as the system requires it, fluid will be fed back as by gravity from the reservoir.

At times I find it advantageous to design the cooperating base plate or header so that both A and B valves are operated simultaneously in the same effective direction from the same pressure source. In such case, to illustrate, high pressure fluid may enter, for example, at both A3 and B3 at the same time, coursing to A7 and B7, respectively, and moving A piston to the left and B piston to the right in Figure 5. Then A3 connects with A2 and B3 with B2, both passing fluid to bore B2. Exhaust fluid courses from A4 to A1, and from B4 to B1, and thence to A6 and B6, respectively. From 16 the fluid courses to 27 and thence to 28, in manner already described. The larger volume of fluid thus handled effectively precludes danger of pumping air from or to the expansion tank which may be placed on the exhaust side of the system controlled by this valve.

It is to be noted that immediately upon removal of a condition of hydraulic unbalance from the system, as upon deenergization of the energizing pump or pumps, the springs at each end of the piston valve elements will restore these elements to their rest position, corresponding to hydrostatic balance. In these positions the valve

elements block the pressure ports A1, A3 and B1, B3, and isolate uniflow outlet ports A2, B2 and exhaust ports A5, A6, B5 and B6, respectively. I have found that by constructing piston valves of the spool type, which have quick opening and closing characteristics, I achieve the advantages that both pressure ports are blocked simultaneously, and at the same time, detrimental wire drawing is substantially eliminated.

Connecting ports A5, A6, B5, B6 to common passages or bores inside casing 10 contributes appreciably to the simplicity, economy and efficiency of design, and permits making the valve compact and rugged in construction. Simplicity of design, ruggedness of construction, and diminished first cost are also contributed to by channeling outlet port A2 into bore B2. By mounting the valves A and B in the single casing, each with its attendant complement of piston valve elements, ports, etc., important economies in size, constructional costs, etc., are obtained, without detracting in any way from overall efficiency, ease of access for overhauling and repairs, and the like.

The low pressure side of the line is always connected to a suitable return circuit, in closed connection, regardless of the direction of flow of the pressure source. The storage reservoir, such as an expansion tank, with which my new valve may be associated, serves effectively to remove temporarily excess fluid from the system and to restore it automatically as and when, and in the amounts, required.

The A and B valves can be operated separately, alternatively and independently of each other, as when each is handling a comparatively light load; or they can be operated simultaneously and mechanically and hydraulically in parallel, for comparatively heavy loads.

Flow rectification is provided, with discharge through uniflow outlet, in simple and efficacious manner.

I claim:

1. As a new article of manufacture, a hydraulic direction-rectifying valve, comprising a multi-ported, longitudinally-bored valve casing, and including pressure ports for connection across a reversible-direction source of pressure fluid for selectively leading in the pressure fluid, a uniflow high pressure outlet port for transmitting the pressure fluid away from the valve, passages branched one off each said pressure inlet ports connecting the same to a corresponding end of the bore, exhaust ports flanking said pressure ports, and a spool-valve element having spaced enlarged diameter portions slidable within said bore and having a position closing said pressure and outlet ports from each other, each of said passages admitting pressure fluid to its end of the bore dependent upon the direction of energization of the pressure source, to move said spool-valve element, the ports and valve element being so related that upon movement of said valve element in either direction within said bore, fluid circuits are completed from the momentarily high pressure port to the outlet port, from the low pressure end of the bore to the low pressure port, and from the low pressure port to the associated exhaust port.

2. A dual hydraulic valve comprising a casing; valve bores in said casing; balanced spool-pistons, one in each said bore; fluid inlet and outlet passages leading through said casing, one

pair of inlet passages and one outlet passage to each said bore, certain of said enlarged portions closing the respective inlet and outlet passages from each other in one position and having spaced enlarged diameter portions for sliding along the same; fluid connections leading from the ends of each piston bore individually to the inlet passages, for conducting pressure fluid to effect longitudinal displacement of the associated piston; and a uniflow outlet passage from each said bore for connection, by means of the corresponding piston, with the momentary high pressure inlet passage upon movement of the corresponding piston enlarged diameter portions out of said closed position.

3. A dual hydraulic valve comprising a casing; valve bores in said casing; balanced pistons slidable one in each said bore; fluid inlet and outlet passages leading through said casing, one pair of inlet passages and one outlet passage to each said bore, each of said pistons having a position closing its inlet and outlet passages from each other; fluid connections leading from the ends of each piston bore individually to the inlet passages, for conducting pressure fluid to effect longitudinal displacement of the associated piston; uniflow outlet passages from said bores, for connection by means of the corresponding piston, with the momentary high pressure inlet passage upon movement of the corresponding piston out of closed position; and a fluid exhaust passage common to each of said piston bores for connection by means of each of the pistons with the associated momentary outlet passage.

4. A dual hydraulic valve comprising a casing having a pair of valve bores therein; a pair of balanced pistons slidable one in each of said bores; and spring means on each end of said pistons for maintaining the same in a mid-position in said bores, said casing having fluid inlet and outlet passages leading through the same with one pair of inlet passages and one outlet passage to each said bore which are closed from each other in the normal balanced position of the pistons, fluid connections leading from the ends of each piston bore individually to the respective inlet passages for conducting pressure fluid to effect longitudinal displacement of the associated piston, uniflow outlet passages from said bores, for connection by means of the corresponding piston, with the momentary high pressure inlet passage upon movement of the corresponding piston out of closed position, and a fluid exhaust passage common to each of said piston bores.

ALBERT GIRVIN WINCHESTER.
